ADJUSTABLE TRANSFORMER

Charles Philippe Boucher, Paterson, N. J., assignor to Boucher Inventions, Ltd., Washington, D. C., a corporation of Delaware

Application November 10, 1939, Serial No. 303,886

4 Claims. (Cl. 171—119)

My invention relates to the operation of fluorescent, luminous gas discharge tubes and to transformer apparatus for operating such tubes.

An object of my invention is to produce a method of operating, in extremely simple and highly efficient manner, fluorescent, luminous gas discharge tubes, so as to produce a mellow light of satisfactory brilliance, which is free of stroboscopic effect, and which can be maintained at substantially constant intensity of light emission throughout the useful life of the tubes.

Another object is to produce a method of operating such tubes which is characterized by the high light emission per unit of energy input, the low operating costs attendant upon the use of the method, the avoidance of danger of overloading the power equipment, and the realization of the desired results with but a minimum of modification of existing equipment.

Another object is to produce a silently operating, substantially fool-proof system of one or more fluorescent, luminous gas discharge tubes and their energizing equipment, acceptable to the Fire Underwriters, and employing extremely simple, and durable, comparatively inexpensive, high voltage transformer equipment, and which system is characterized by the cool operation of the tubes, the long life of the component parts of the system, the markedly increased light emission per unit of energy input, and the simplicity of all electrical connections employed; and which system possesses marked flexibility, being adaptable to substantially any reasonable size or configuration of tubing desired.

Still another object is to produce a new constant current transformer for use with negative loads, which is characterized by its simplicity, durability, long life, and low investment both initially and in maintenance, and which can be adjusted at will and with great sensitiveness to produce a desired maximum current flow in the transformer secondary winding, up to the ultimate maximum current-carrying capacity of the transformer.

Other objects in part will be obvious and in part pointed out hereinafter.

The invention accordingly consists in the combination of elements, features of constructions, and arrangement of parts, and in the several operational steps, and in the relation of each of the same to one or more of the others, all as described herein, the scope of the application of which is indicated in the claims at the end of the specification.

Referring now more particularly to the draw-

ings, Figure 1 is a schematic front elevation view and Figure 2 a corresponding side elevation view of a transformer and tube assembly embodying my invention.

5 Figures 3, 4 and 5 are fragmentary front elevations showing details of several forms of magnetic by-passes for transformers according to my invention.

Figure 6 is a detail of an embodiment of my 10 invention, wherein the air-gap of the magnetic by-pass for the transformer is bridged by a rotor, rotatable to vary the effective dimensions of the air-gap.

Figure 7 shows in elevation the details of a 15 swingable bridging member, while

Figures 8 and 9 are corresponding end and 20 front elevations of an embodiment wherein a strip of magnetic material is used to bridge so much of the air-gap of the magnetic by-pass as is desired.

Like reference characters denote like parts throughout the several views of the drawings.

As conducive to a more thorough understanding of my invention, it may be noted that for a 25 number of years, illuminating engineers have relied upon the nitrogen-filled, tungsten filament electric light bulb as by far the principal source of artificial light. This light source gives a very satisfactory white light of considerable brilliance. It is found, however, that the major portion of the electrical energy input to such bulbs is dissipated in the form of heat. This is conservatively estimated as being between 90% and 95% of the energy input to 30 the tube. The energy dissipated at best represents a complete loss, leaving only between 5% and 10% of the input energy converted into useful visible radiation.

More and more mercury vapor lamps have 40 come to replace incandescent lighting and recently fluorescent luminous gas discharge tubes have begun to replace the known tungsten filament bulbs. The luminous tubes comprise a narrow, elongated glass tubing, the inner wall of 45 which is coated with some suitable fluorescent salt, well known in the art, and the particular type of which largely determines the color and quality of the radiation emitted. The salt is energized from any suitable source of radiant energy, such, for example, as a mercury vapor arc. The radiation emanating interiorly of the tube from the glow or diffused arc discharge occurring through the mercury vapor or other suitable gas, although perhaps of wave-length 50 too short to register on the naked eye, strikes

against and energizes the fluorescent salt. These salts, thus excited, then give rise to a steady continuous radiation of visible mellow light characteristic to the particular salt or combination of salts used. A tube thus operated is found to run cool, and inasmuch as its emission is continuous, there is a total absence of objectionable flicker, known as stroboscopic effect, such as is encountered where the light-emitting source is energized directly from an alternating current source. Thus the flicker, noticeable when an ordinary bare mercury arc lamp or a tungsten filament bulb is energized by a 60 cycle current source and particularly objectionable when a 25 cycle energizing source is employed, and which has a frequency of $\frac{1}{120}$ or $\frac{1}{60}$ of a second, respectively, is completely avoided. Such tubes are found to have a light-emitting efficiency many times that of the ordinary incandescent lamp or, in other words, their light emission per unit of energy input is much greater than that of the conventional tungsten filament lamp. In point of fact, such fluorescent white light has been found to be the most economical source of artificial white light known, so far as concerns power consumption.

Because of these marked advantages, fluorescent tubes are employed not only in commercial and industrial installations, but have recently come into rather widespread use in household, store, and other interior lighting. Such tubes have recently been developed for operation at ordinary household voltages, such as 110 and 220 volts.

It has been found that, while the efficiency of light emission from such tubes is great, the brilliancy or total emission of light is not nearly so large as that of filamentary lamps. Accordingly it has become the practice to operate these tubes in multiple, to build up the total light emission to the required value.

A fixture is provided for receiving these tubes, and the tubes themselves are handled and sold as are ordinary electric bulbs. When the useful life of the tube is terminated, it is simply replaced in the fixture. I find that these tubes produce an average of 30 to 40 lumens per watt input, for the extent of their useful life, which, when operating under favorable conditions, is about 2000 hours.

Certain disadvantages have been encountered in the practical utilization of low voltage fluorescent tubes. In the arrangement of such tube lighting now in use, one disadvantage is a high initial cost of equipment. It has been found that a 110 volt potential will energize no more than about 24 inches of tubing. Where such a tube is connected directly to household mains, a current limiting device must be used for each 24 inch section of tubing, a resistor being commonly used for this purpose. Furthermore, a heater must be provided for each unit to bring the mercury filling to a point where an arc can be struck at 110 volts. Thus, if a tube 6 feet in length is desired, it is obvious that the tube must be laid into sections no more than 24 inches in length and that for each section resistors, heaters, and current-carrying electrodes must be provided.

Furthermore, it has been observed that after fluorescent tubes have been in operation for some 10 to 15 light hours, their original brilliancy diminishes materially, or, in other words, their light emission for a constant energy input decreases considerably. This condition of diminished brilliancy continues at about a constant level for some time, about two thousand light

hours, when a further decrease in unit light emission is encountered. This final decrease necessitates replacing the tube by a fresh one. One possible explanation for this phenomenon of decreasing brilliancy is that it is due to deterioration of the fluorescent salts with which the inner wall of the tube is coated, but the exact nature of this occurrence is not now known so far as I am aware.

The decrease in emission of light and consequent early discarding of the tubes cause a high cost of maintenance and replacement. Because of the importance of this element of cost, the introduction of such tubes into new fields of illumination has not been quite so widespread as it would otherwise be, particularly in the case of those tubes designed and constructed for operation at low voltages.

The greatest disadvantage of these tubes is experienced when it becomes necessary to replace them in operation. When a tube is discarded, with it must be discarded the electrodes and heaters. Where a pair of electrodes, a heater, and a current-limiting device are provided every twenty-four inches, it will readily be appreciated that the investment discarded upon scrapping a tube is relatively high.

Another disadvantage of these tubes for low-voltage use is that, in requiring complicated installations of heaters, current-limiting devices, and electrodes, the service charges for installing them are high since only skilled labor can satisfactorily carry out the operational steps required.

An important object of my invention, therefore, is to produce a system of fluorescent, luminous gas discharge tube energizing equipment, and a method of operating the same in simple, efficient and economical manner, at high voltages, with long life and with constant intensity of light emission, in which the cost of replacing the parts thereof is low, which entails a minimum expenditure for labor in installation and maintenance, and which is entirely acceptable to the Fire Underwriters.

Despite the disadvantages pointed out in the foregoing, it appears, as already pointed out, that fluorescent tubes are becoming more and more used for illumination purposes, displaying a strong tendency to replace ordinary incandescent lighting systems. Their efficiency, mellow light, and low temperature of operation make their use advantageous, so that it is most desirable that a system using these tubes be designed in which a constant emission of light, long life, and steady operation are obtained.

It may be stated in general that one of the objects of my invention can be accomplished by operating the fluorescent tube or tubes at comparatively high voltage, and by increasing the current input to the tube as the light emission thereof per unit of power input decreases, in such manner, and in such proportion to the said unit decrease of light emission, that the total light emission from the tube is maintained substantially constant.

As illustrated in general in Figure 1, my invention comprises a new form of constant-current transformer, and a system consisting of such a transformer and a negative load therefor. My invention also comprises a method of operating such system. The transformer includes a core having legs 10, 11, 12 and 13, forming a closed path. Primary coil section 14 is mounted on leg 10, while secondary coil sections 15 and 16 are mounted on leg 12. Straps 17 and 18 conveniently are provided, preferably of paramagnetic

material, such as steel, for securing the laminations of the core parts against chattering.

Primary winding 14 is connected by suitable leads 19, 20 to a source 21 of single-phase alternating current electrical energy, such as the usual 110 volt or 220 volt commercial source.

The secondary coil sections 15 and 16 are connected together in series by way of conductors 22 and 23. The two coil sections thus forming the secondary winding are connected by way of conductors 25 and 26 to the fluorescent luminous gas discharge tube 27 or other load. In order that the potential to ground shall not exceed a value permitted by the Fire Underwriters, and yet maximum voltage be available for tube energization, the interconnections between coil sections, that is conductors 22 and 23, are connected to core 12 which in turn is grounded as at 24.

The luminous tube 27 comprises an elongated piece of glass tubing, coated on its interior wall with a suitable fluorescent salt. The tube is of proper length and configuration to produce the desired illumination. Simple and conventional electrodes of suitable type are provided, one at each end of the tube. Since the brilliancy of illumination of these tubes is found to vary inversely with their cross-sectional diameter, I prefer to form them from small diameter tubing. It will be appreciated that one important advantage of the use of such tubing, as compared with other low voltage tubes recently made available for use, is their extreme simplicity, making it possible for anyone equipped to produce the conventional neon tubes, to manufacture these fluorescent tubes with but little if any additional equipment, and this of a very simple and inexpensive type.

While the load has been shown as comprising a single tube 27, it is of course, apparent that it may comprise any number of tubes connected either in series or in parallel. Moreover the secondary coil sections 15, 16 can be connected to the load either in series, as illustrated in the drawings, or in parallel, depending upon whether the coil sections themselves are so related to each other and to the core as to be in series-aiding or in series-opposition (bucking).

An important requirement of the transformer according to my invention is that it be provided with a magnetic shunt path to limit the current output of the secondary coil sections. In practice my transformer is designed and calibrated for a certain maximum secondary current output, and this output is limited by the shunt. Such shunt employs one or more magnetic flux by-passes having a predetermined reluctance.

Usually these by-passes include one or more air-gaps. The construction preferably is such that nothing can cause the transformer secondary winding to develop a current in excess of the maximum rated secondary current. This means, where a magnetic by-pass having a fixed air-gap is employed, that the shunt preferably should be integral with the core proper and the air-gap mechanically set. These shunts may be disposed either externally or internally of the secondary coil sections. By that I mean that the shunt about a secondary coil section is disposed either externally or internally of the outer confines of the main core of the transformer. In the instance of a transformer of internal shunt construction, provision is made for means extending externally of the casing, for manipulation of the shunt in accordance with my invention.

At the present time, I believe the external shunt to be more practical in connection with my invention, and such an external shunt is illustrated in the transformer of Figures 1 and 2. However, I do not desire to be bound by my present preference for the use of external shunts, for it may well be that further investigation will demonstrate that internal shunts, such as those illustrated in the transformers of Figures 8 and 9, are of equal advantage in connection with my invention.

Considering more particularly the core construction, leg 12 preferably is provided, as shown in Figure 1, with a substantially T-shaped core extension 28, having heads 28a and 28b. This T-shaped extension protrudes outwardly from leg 12, between and beyond the secondary coil sections 15, 16. The heads 28a, 28b extend laterally from the center leg of core extension 28, substantially parallel with and in spaced relation to the leg 12. Similarly, legs 11 and 13 are provided with extensions 11a and 13a, preferably of reduced cross-section. These last-mentioned extensions protrude beyond the symmetrical confines of the core from the same end thereof and in the same direction as protrudes the core extension 28. The extensions 11a and 13a extend closely adjacent to but separated from heads 28a, 28b, respectively, by the short air-gaps G1 and G2.

The by-passes for the magnetic flux serve to shunt part or all of the flux coursing the main core around the secondary coil sections, the air-gaps included in the by-passes limiting this shunting action. It will be evident that in general, upon decrease in the reluctance of the by-pass, as by limiting the effect of the air-gap, the greater will be the proportion of the flux which is shunted through the by-pass, and the lower will be the proportion of the flux traversing the core 12 and hence the lower will be the current output of the secondary coil sections 15, 16. Carried to its ultimate end, as by completely eliminating the effect of the air-gap, a condition can be obtained such that practically no current can flow through the secondary coil sections. For such adjustable control, adjustable partial bridging of the air-gaps is provided. Where no gap is used in the by-pass, the control can be accomplished by providing means for increasing and decreasing the effective cross-section of the by-pass.

Where a shunt construction including an air-gap is employed, I procure effective control of the air-gap in one of three principal manners. One of these is to provide a fixed air-gap and provide an adjustable bridge therefor. Another is to vary the length of the air-gap, while yet another is to vary the effective area thereof. Many modifications in each of these three categories may readily be realized.

In the example of Figures 1 and 2, I employ a fixed, external air-gap. Control of the effectiveness of the by-pass is obtained by the use of bridging means in the form of magnetic blocks 29 and 30. These bridging blocks 29, 30 are formed of laminated highly magnetic material, such as silicon steel, cast iron or the like. As stated, the air-gaps G1, G2 are of fixed width and cross-sectional area. Any change in the reluctance of such air-gaps will result in change in the secondary current. Thus as already suggested, complete bridging of the air-gaps by magnetic material will render the air-gaps ineffective. 75 Substantially all the flux would course the low

reluctance by-passes, and practically no flux would pass through the core 12 and very little current would flow through the secondary coil sections. A partial bridging of the air-gaps G1, G2 will bring the value of the maximum current which can flow in the secondary coil sections to a certain predetermined minimum, sufficient to energize effectively the tube load 27 when the tubes are first installed.

Bridging blocks 29, 30 serve to permit the partial bridging of the air-gaps included in the shunt paths. Each block preferably is divided into a selected number of sections or stacks. In the embodiment shown, referring to Figure 2, there are in each block three stacks 29a, 29b, 29c, and 30a, 30b, 30c, respectively. The operation of these blocks will be described hereinafter.

Since, as has been stated, the effect of the bridging blocks, unless precautions to the contrary are taken, is to completely short the air-gaps G1 and G2, I find it advisable to interpose a membrane 31 between the air-gaps and the bridging blocks. This membrane is made of suitable non-magnetic material, either metallic, or non-metallic, such, for example, as aluminum, brass, Bakelite, fiber, paper or the like. Thus, when intimate contact between the magnetic by-passes and the bridging blocks is prevented, it is possible for the primary flux to build up a voltage in secondary coil sections 15, 16 sufficient to strike an arc across tube 27.

My transformer may be of the core and coil type, that is, having no container and no insulating compound and in which the coil terminals are replaced by flexible leads, or it may be provided with a casing and a filling of suitable insulating compound. In the transformer according to Figures 1 and 2, I prefer to provide a casing 32 having a base 33 and a cover 34, all preferably formed of some suitable inexpensive material such as steel or iron. This casing fits snugly about the transformer, and preferably has in one side thereof a window 35 (Figure 2) which is covered by membrane 31. This membrane may be soldered, spot-welded, riveted (Figure 2), or otherwise securely fitted to casing 32, as indicated at 36, thereby sealing the insulating compound against leakage.

Blocks 29 and 30 preferably are enclosed snugly in small metal containers 31, one of which is shown partly broken away over the block 29, and which I prefer to make fast to casing 32. These containers provide a very convenient way of mounting the blocks, and also serve to prevent undue humming.

In the operation of my transformer, at the first part of a given half-cycle, with flux coursing as indicated by the arrows, the voltage induced in coil sections 15, 16 is not sufficient to strike an arc. Hence no current flows in the coil sections and consequently no magnetomotive force opposing the main flux is developed. Therefore, the core leg 12 forms the path of least reluctance, and most of the flux courses this leg interlinking the secondary coil sections. At the moment when the induced secondary terminal voltage reaches a value sufficient to strike an arc across tube 27, however, the tube resistance drops and a surge of current occurs through the tube. This current, flowing through coil sections 15, 16, generates a flux tending to flow in a direction counter to the main flux, bucking the main body of flux and causing it to seek the path of least reluctance. This path is then the magnetic by-pass constituted by leg extension 11a, air-gap G1, head 28a, 75

head 28b, air-gap G2, and leg extension 13a. Just enough flux courses leg 12 to insure development of sufficient voltage in the secondary coil sections to energize tube 27 in its conductive condition.

During the latter part of the half-cycle in question, the value of the flux decreases, until a point is reached where the developed voltage is no longer sufficient to maintain the arc across the tube. The arc then extinguishes and current flow stops. Immediately the generation of counter flux terminates, and the main body of flux, no longer impeded, resumes its coursing of leg 12.

In the next half-cycle, the direction of coursing of flux is opposite to that of the arrows. Until the generated voltage reaches the striking potential of the tube, the flux courses leg 12, in an upward direction in Figure 1. When the arc is restruck, the counter magnetomotive force generated bucks the main body of flux, forcing the major part to course the by-pass 13a, G2, 28b, 28a, G1 and 11a. Finally, in the latter part of this second half-cycle, the value of flux diminishes until the generated voltage is no longer sufficient to maintain the arc discharge, the tube extinguishes, and due to absence of counter magnetomotive force the main body of flux again courses leg 12.

Under full short-circuit conditions, a current begins to flow in the secondary coil sections 15 and 16 immediately upon the flux building up in core 12. Back magnetomotive forces are developed in these coil sections from the outset, therefore, which oppose the growth of flux in core portion 12. As a consequence, a large part of the magnetic flux traverses the by-pass or shunt path 11a, 28a, 28b and 13a provided for this purpose, this path including the two air-gaps G1 and G2. In other words, the transformer operates very much as it does under ordinary load conditions, the current in coil sections 15 and 16 being limited to safe values by virtue of the shunting of magnetic flux linking these coil sections as noted above.

Where a short-circuit develops across but a single coil section of the secondary winding, an entirely different situation obtains in the flux path. By virtue of the short-circuited condition of the one coil section, a current flows and a back magnetomotive force is developed by the flow of current from the initial period of the applied potential. In the other coil section, however, no current flows and no back magnetomotive force is developed because the reduced potential applied to the luminescent tube ordinarily is not sufficient to establish the glow discharge conditions in the tube. The total back magnetomotive force opposing the coursing of flux through core portion 12 therefore is only that developed by the current in the one short-circuited coil, that is, about half of that developed under load conditions or full short-circuit conditions. This would lead to an excessive flux linking the short-circuited coil but for the fact that a shunt path of but one-half the reluctance of that ordinarily encountered is now presented. The main body of flux is shunted around the short-circuited coil over a path including but a single air-gap. For example, upon short-circuiting the single coil section 15, the main body of flux would be shunted along the path of core portion 11a, 28a, 28 and lower part of core 12. This path includes but the single air-gap G1. It will be understood that a short-circuiting of the one coil 16, instead of coil 15, will cause the flux

path to be shunted around that coil section through core portion 13a, 28b, 28 and the upper part of core piece 12, a path including but the single air-gap G2. In both cases, the reluctance of the leakage flux path is less than that where load or full short-circuit conditions prevail.

Referring now back to my system as a whole, it has been pointed out that operation of fluorescent luminous gas discharge tubes has led to the discovery that after a short period of operation the brilliancy of the tubes decreases appreciably, and then after some hours of operation again decreases a further appreciable amount, at which time the tubes must be discarded. The tubes, which are comparatively costly, have had a useful life in the neighborhood of but 2000 hours, particularly where low voltage equipment has been employed.

Reference has been made to an important object of my invention comprising the operation of the tube at comparatively high voltages with the light emission of the tube being maintained substantially constant throughout the useful life of the tube. This goal is accomplished by increasing the current capacity of the transformer from time to time, as the unit emission of the tube or light output per unit of energy input falls off. The increased input thus provided is sufficient to produce a light emission of desired constant value.

For illustration, assume the transformer of Figures 1 and 2 to be designed for a maximum short circuit current of say 45 milliamperes and that the bridging blocks 29, 30 serve to reduce this current to 25 milliamperes. Assume also that tube 27 has been designed to operate initially at say 20 milliamperes, at which time its efficiency of light emission will be at a maximum. Regulation of current input is then accomplished in the embodiment of Figures 1 and 2, employing a fixed air-gap, by varying the dimensions of the bridging blocks 29 or 30 or both. As can best be seen in Figure 2, one or more sections of the sectional bridging block can be removed when necessity for increased current flow arises.

As a result of this removal, the reluctance of the magnetic by-pass increases and its shunting action correspondingly diminishes, more flux coursing the core leg 12, and more current being developed in secondary coil sections 15, 16. This regulatory manipulation can be made at each time there is appreciable diminution in the intensity of light emission from tube 27 until the bridging blocks are entirely removed, leaving the magnetic by-passes with greatest reluctance. At this point the tube 27 will operate with required light emission at about 35 to 40 milliamperes input. The transformer and system are preferably so dimensioned that the useful life of the tube is ended when more than 40 milliamperes input is required to produce a satisfactory illumination. Upon occurrence of further decrease in light emission from the tube, at 40 milliamperes input, this tube is discarded and is replaced by a new tube, and the sections of the bridging block are replaced.

I prefer to have the magnetic sections of my bridging blocks replaced by sections of non-magnetic material of the same dimensions when the former are removed from their containers 37 in adjusting the reluctance of the shunt path. By this means I completely fill the containers 37 so that humming or chattering is minimized throughout the various stages of use of the transformer.

In the illustrated embodiment, the air-gap is bridged on one side only. It is apparent, however, that a more positive result is obtainable by bridging two, three or four sides thereof. Also, the reluctance of the air-gaps G1 and G2 can be varied by adjusting the positions of the magnetic blocks 29 and 30 at different distances from the air-gaps. This can be done by suitable mechanical means. If a perfectly constant light is desired, a selenium cell may be used to control the mechanical means.

While in the embodiment of Figures 1 and 2, I have elected to employ a transformer secondary winding consisting of two secondary coil sections connected in series, it is equally feasible to employ but a single secondary coil section for any one secondary winding. Such construction I have shown in Figure 3. As illustrated in that figure, I mount a single secondary coil section 115 on core leg 112. The coil section 115 is shunted externally thereof by a substantially C-shaped magnetic by-pass, having an air-gap G3. An important feature of this construction is that, unlike the embodiment of Figures 1 and 2, the component parts of the magnetic by-pass are wholly separate from the main core. Thus, the by-pass comprises bar-member 38 and L-shaped member 39, both being separate from the core 112. Since the air-gap G3 between these two members must be fixed to ensure predictable operation of the transformer, I find it convenient to fill the air-gap with non-magnetic material 40 to maintain the air-gap at its proper value. The material 40 may, for example, take the form of shims of cardboard, fibre or the like. A membrane 131 of non-magnetic material is provided, the purpose of which, just as in the embodiment of Figure 1, is to decrease somewhat the direct shorting effect of magnetic bridging block 129.

In the embodiment of Figure 4, which is illustrative of another possible modification, I combine certain of the features of the examples of Figures 1 and 3. Here, just as in Figure 1, I mount on the core leg 212, secondary coil sections 215, 216. Core extension 228 extends centrally from and at right angles to core leg 212 between said coil sections; and similarly to the embodiment of Figure 1 terminates in heads 228a, 228b. Thus, the core extension may be said to be T-shaped. In lieu of the extensions 11a, 13a of the transformer of Figure 1, in this embodiment I provide separate bar-members 41, 42. Between head 228a and member 41 is formed air-gap G4, while between head 228b and bar-member 42 is formed air-gap G5. Since members 41, 42 are separate from the main core structure and hence are susceptible to movement relative thereto, proper dimensioning of the fixed air-gaps G4 and G5 is ensured by inserting non-magnetic and preferably non-metallic spacers 43, 44 in the air-gaps. The magnetic regulatory action of the T-shaped core extension 228, 228a, 228b is the same as previously described with reference to Figure 1.

As a possible alternative for the use of two bridging blocks, one for each air-gap to be regulated as in the transformer of Figure 1 in the construction illustrated in Figure 4, I employ but a single elongated magnetic bridging block 45 common to and controlling with equal effect the air-gaps G4 and G5. This bridging block is laminated and I prefer to form it of silicon steel, cast iron or the like. This construction has the advantage over that of Figure 1 of simplicity, ease of installation, slightly less humming in op-

eration, and ready adjustment thereof. It is somewhat less sensitive in its control action but I find that it may be employed advantageously where some diminution of light emission may be permitted before correction is required.

In the example of Figure 1, I prefer to form straps 17, 18 of steel or iron. In the construction of Figure 4, where I provide the strap 217 encircling the heads 228a, 228b and bar-members 41, 42, I find it advisable to construct the straps of some suitable non-magnetic material. This is done because a paramagnetic metal, such as iron or steel, would tend to act as a magnetic short or jumper across the air-gaps G4 and G5 thus destroying their regulatory action.

As a further example of an external magnetic by-pass having a fixed air-gap, reference is to be had to Figure 5. In the embodiment therein, secondary coil section 316 is mounted on core leg 312, which at one end abuts in suitable manner core leg 313. One noteworthy feature of the illustrated construction is the provision of cooperating positioning notches and grooves in the juxtaposed parts of the transformer core. Thus a notch 46 is formed in core leg 313, to cooperate with and receive a complementary-shaped protuberance 47 in core leg 312. By assembling the core parts with their notches and grooves in proper engagement, desired alignment of the several parts is ensured with but a minimum of labor and effort.

Core leg 312 in Figure 5 is provided as illustrated, with a laterally and outwardly extending L-shaped extension 48, the outer part 48a of which, being parallel with leg 312, extends to a point just short of leg 313 to form a fixed air-gap G6 therein of desired dimensions. Thus, as illustrated, the upper end of leg 313, the air-gap G6 and L-shaped extension 48a together form a magnetic by-pass externally shunting the flux and controlling its interlinking with coil section 316. Bridging block 330 is provided for spanning the air-gap. It carries out its regulating action by movement thereof either from left to right in Figure 5, or by movement towards or away from the plane of the paper. As a possible alternative, it may control the reluctance of the air-gap by being moved bodily towards and away from the leg 313 and extension 48a. Its effect is minimized to a desired extent by the interposition of a membrane 331 of non-magnetic material. Because all parts of the core construction are fixed with respect to each other, the spacers 43, 44 of Figure 4, and spacer 40 of Figure 3, may be eliminated in this example.

In the embodiments hitherto described, adjustment of the reluctance of the magnetic by-pass, and hence of the current developed in the transformer secondary, has been accomplished by bridging a fixed air-gap. It is of course thoroughly practical to construct the magnetic by-pass so as to have therein a variable air-gap, and to vary the air-gap to produce the desired regulation. Many manners of varying air-gaps will suggest themselves, and one such possible construction, employing a rotor in the air-gap, is illustrated in Figure 6. Therein a core leg 412 has a secondary coil section 415 mounted thereon, one-half of which is illustrated. Shunt elements 49, 50 are secured in any desired manner in abutting relation to leg 412, and extend in parallel manner laterally and outwardly from core leg 412. These shunt elements 49, 50 are on opposite sides of coil element 415 and thus

comprise an external shunt. These elements, moreover, extend outside of casing 431.

Between elements 49, 50 at the free ends thereof, is formed an air-gap G1. Mounted in 5 suitable manner centrally in the air-gap is a rotor. This rotor has a hub 51, rotatable about a spindle 52. A handle 53 is provided, to facilitate manual rotary movement of the rotor. The action of this handle is purposely made moderately frictional to prevent unintentional manipulation of the rotor. A bridging element 54, fast on hub 51, completes the rotor. This rotor has cylindrical surfaces 55, 56, co-axial with spindle 52. The corresponding faces 57, 58 of 10 the shunt elements 49, 50 are also cylindrical and concentric with the surfaces 55, 56 to ensure an air-gap G1 of uniform clearance at all points, regardless of the angular position of the rotor.

With the rotor in the full-lined position illustrated, the air-gap is of minimum reluctance, and the current developed in secondary coil section 415 is just sufficient to satisfy the initial requirements of the tube load, when it is first 15 installed for operation. As the tube ages, and unit light emission falls off, so that increase of available current is required, it is possible to increase the reluctance of the air-gap G1 by changing the dimensions of the latter. Thus, by manipulating handle 53 to turn the rotor slightly, the effective area of the air-gap is decreased. Or what is magnetically equivalent to the foregoing, the effective volume of the bridging block is decreased. With the consequent increase in 20 reluctance of the magnetic by-pass more current is developed in the secondary coil section and the light emission from the tube load is restored to its initial value. The rotor may be turned to the extreme position illustrated in dotted lines 25 in Figure 6, at right angles to its original position at which time the reluctance of the magnetic by-pass is at a maximum. The effect of the by-pass is at a minimum, and maximum current now flows through the secondary load. I have 30 found that a construction, such as described, while structurally simple and easily adjusted, possesses the disadvantage of being somewhat noisy in operation.

A further possibility for regulating the air-gap of a magnetic by-pass involving movement 35 of an armature, thereby directly affecting the length of the air-gap, is illustrated in Figure 7. Therein, core leg 512, coil section 515 and casing 532 are depicted. Upstanding shunt elements 61, 62 extend laterally and outwardly in 40 parallel relation from leg 512 at right angles thereto and on opposite sides of coil section 515.

Armature 63 is hinged at 64 to element 62 and is provided with projecting bars 65 which are 45 secured in adjusted position on threaded spindle 66 by suitable means such as nuts 67, 68. Where desired, other suitable means may be employed for adjusting and securing the bridging block in angular position, and the means shown are purely 50 by way of illustration and are not limitations.

In the full-line position of armature 63, the latter establishes the minimum lengths of air-gaps G8 and G9 formed between the armature and elements 61 and 62, respectively. The 55 lengths of the air-gaps are at a minimum and therefore the reluctance of the shunt path is at a minimum. This corresponds to the condition of initial installation of a tube in the system requiring minimum current for rated light emission.

Upon an aging of the tube and a decrease in its emission of light, a greater flow of current to restore rated conditions is necessary. This is had through increasing the reluctance of the external magnetic shunt or by-pass. In the illustrated embodiment, this is accomplished by slight readjustment of armature 63 from the full line position to the angular dotted position, as by manipulation of nuts 67, 68. This effectively increases the length of the air-gaps thereby decreasing the quantity of flux coursing the shunt path during the ignition of the tube load and consequently increasing the flux linking primary and secondary windings and increasing the output current.

While in the examples shown I have disclosed the construction only of magnetic by-passes disposed externally of the core, it is equally feasible, of course, as I have already suggested, to construct such by-passes internally of the core. It is also possible to construct a magnetic by-pass in which the air-gap is regulated by sliding, in a flat air-gap, a flat, accurately dimensioned piece of magnetic material, the position of the said piece relative to the air-gap determining the effective bridging of the latter.

A construction combining both these possibilities is illustrated in the shell-type transformer of Figures 8 and 9. In this embodiment the core comprises main leg 71 on which primary coil section 614 and secondary coil section 615 are mounted. Core legs 72, 73, 74, 75 are also provided. Brackets 76, 77 serve to prevent chattering of the laminations of the various core elements. Rivets 78 secure the brackets to the core laminations.

The main leg 71 is preferably oriented properly with respect to legs 72, 75 by cooperating notches and grooves 81, 82. Main leg 71 is provided, between the primary and secondary coil sections 614, 615, with outwardly protruding right-angled extensions 71a, 71b, extending on opposite sides thereof to points just short of legs 73, 74, respectively, and respectively forming therewith the air-gaps G10, G11. Bridging members 83 and 84 are provided for air-gaps G10 and G11 respectively in order to increase or decrease the efficacy of the air-gaps, as more particularly pointed out hereinafter.

With flux coursing momentarily in the direction of the arrows and assuming that the flux has not yet built up a voltage in the secondary coil section 615 sufficient to strike an arc across the tube comprising the load, the flux developed in the primary coil section courses upwardly through main leg 71, splitting into two parallel paths in leg 72, one of these paths extending through leg 73, the left-hand portion of leg 75 and back up through leg 71, thereby interlinking coil section 615. The other path is through leg 74, the right-hand portion of leg 75 and up through main leg 71 to complete the circuit and link coil 615.

When an arc is struck across the tube load of the transformer, current flows in coil section 615 building up a counter magnetomotive force which bucks the main body of flux. The major part of the main body of flux then courses the path which is momentarily of least reluctance. It flows, by consequence, upwardly through leg 71, thence in two paths through leg 72, downwardly in parallel paths through legs 73 and 74, thence across air-gaps G10 and G11, extensions 71a, 71b, and the two parts reuniting in leg 71 to complete the circuit linking only the primary winding 614. Just sufficient flux courses the lower

part of main leg 71, and links the secondary winding 615 to insure development of the required current.

Similarly, with reversed coursing of flux, before the tube is ignited, the flux courses down leg 71 splitting in two parallel paths at leg 75 and thence courses upwardly through legs 73, 74 to leg 72, where the parallel paths of flux reunite, to continue their journey to primary coil section 614. Thus, the main body of flux interlinks secondary coil section 615 before current begins to flow in this coil section, but when the current is flowing, it causes a counter magnetomotive force to be developed which bucks the main body of flux. Thereupon, the larger portion of the main body of flux traverses a path down through leg 71 in parallel paths through extensions 71a, 71b, up through legs 73, 74 and back through leg 72, reuniting at the top of leg 71. A large portion of the flux is thereby shunted around the secondary coil section 615, and does not interlink this latter.

Now, if it is desired to increase from time to time the current developed in the secondary winding, to compensate for decreased unit light emission in the tube load, this can be accomplished by decreasing the effect of the bridging members 83 and 84 provided for the air-gap control, thereby increasing the reluctance of these latter.

When a fresh tube is initially placed into operation, having its highest unit emission, and requiring lowest unit current, it is desired that the effect of the magnetic by-passes be at a maximum. Accordingly, the reluctance interposed by the air-gaps in the magnetic by-passes should be at a minimum. To insure this condition and with proper design of the constants of the air-gap, the strips 83, 84 will be inserted all the way across the air-gaps, until they abut stops 85, 86. The strips conveniently are steadied by springs 87 and 88 in order to minimize vibration and chattering. The air-gaps G10, G11 are then substantially completely bridged. Thereafter, upon a decrease in the unit light emission of the tube load, the strips 83, 84 are pulled out of the air-gaps to a short extent, thereby diminishing the bridging action, increasing the reluctance of the magnetic by-passes, and permitting a compensating amount of current to flow in the secondary load.

It will be seen from the foregoing that essentially my invention resides in the operation of a fluorescent luminous gas discharge tube by a transformer which is regulated so as to provide additional current upon a falling off of the unit light emission of the tube.

By using high voltages, I am enabled to operate a tube, which, being in one unit, is several times the length of the largest individual unit possible in low voltage installations. Furthermore, there is no need, in my device, of heating coils to assist in striking an arc. Accordingly, I avoid most of the loss incurred in discarding electrodes, heaters and choke coils when low voltage tubes reach an efficiency which is too low to justify their further use.

The use of a fluorescent luminous gas discharge tube ensures a mellow light, the color of which may be selected from a wide range of possibilities, depending upon the particular fluorescent salt or salts with which the inner wall of the tube is coated. Such a tube is readily produced in any shop equipped to produce the present-day conventional neon signs, employs standard electrodes, and operates with great efficiency and with

a high degree of coolness as compared with the usual incandescent lamps. Inasmuch as the visible light emanates from the secondary radiation of the fluorescent salts, when they are energized by the glow discharge between the tube electrodes, a steady light is produced which is substantially free from all stroboscopic effects, or objectionable flicker. Thus, such a light source has a widespread scope of utilization in industrial, commercial and scientific fields, as well as in household lighting. Such a tube is capable of operation at comparatively high voltages, say from two to five thousand volts or more, and as contrasted with known tube equipment constructed for use at ordinary household voltages of say 110 or 220 volts, is characterized by its simplicity, its small number of parts, its greater efficiency, ruggedness, flexibility and its low first cost.

When such a tube is used in a system employing my new transformer, in accordance with the new method set forth hereinbefore, there is obtained for the first time a substantially uniform light emission throughout the useful life of the tube. The life of the tube is greatly increased, and the desired current regulation is obtained in a simple and inexpensive transformer. Regulation of the current output of the transformer is obtained in ready and simple manner. Upon discarding a tube at the end of its useful life, even if the glass and metal parts thereof be scrapped, it will be found that because of the long life of the tube, the low first cost of both the transformer and the tube and the low operating cost, the replacement cost, prorated over the life of the tube measured in light hours, is extremely low.

To summarize briefly, it may be stated that my new invention is characterized, as compared with other high voltage tube operation, by its lower first cost, lower cost of installation, and lower operating costs, all with a useful life at uniform brilliance of more than twice that of fluorescent tube equipment as it is now operated. Contrasted with low voltage fluorescent tube operation, it has a light emission efficiency in lumens per watt slightly greater than such construction, has a much greater life, a lower first cost, produces a steady light by the use of a simple and inexpensive electrodes and is operated by inexpensive transformer equipment. I find, for example, that the combined cost of heaters and choke coils employed for proper operation of low voltage tube equipment exceeds the cost of the transformer equipment used according to my invention.

When weighed against available incandescent lighting equipment, my new invention produces for unit power, from three to four times, up to as high as 5 times, the quantity of light obtainable from filamentary lamps. Furthermore, it possesses the advantage of great flexibility making it possible to construct tubing of any desired shape, up to lengths of fifteen feet or even more, all meeting with the approval of the Fire Underwriters.

As other embodiments and variations may be

made of my invention, and as changes may be made in the embodiments hereinbefore set forth, it will be understood that all matter described herein or shown in the accompanying drawings is to be interpreted as illustrative and not in a limiting sense.

- 5 1. A transformer capable of delivering desired maximum current to its load, comprising a core; a primary winding and a secondary winding on said core; a magnetic by-pass disposed on said core and shunting said secondary winding, said by-pass having an air-gap therein; and a sectional bridging block for bridging said air-gap, removal or addition of sections to said bridging block determining the effective dimensions of said air-gap and hence determining the quantity of flux linking said secondary winding and the value of the secondary current.
- 10 2. In combination, a transformer and a casing of para-magnetic material fitting snugly about said transformer, said transformer comprising a core, a primary winding and a secondary winding on said core, a magnetic by-pass on said core and shunting said secondary winding and having an air-gap therein, and said casing having a membrane of non-magnetic material defining a portion thereof, and adjustable magnetic means mounted on said casing exteriorly of said membrane for controlling the flux across the air-gap in said magnetic by-pass and thereby determining both the quantity of flux linking said secondary winding and the value of the secondary current.
- 15 3. In combination, a transformer capable of delivering desired maximum current to its load, and a casing snugly housing said transformer; said transformer comprising a core, a primary winding and a secondary winding on said core, a magnetic by-pass having an air-gap therein disposed on said core and shunting said secondary winding, and means exteriorly of said casing for bridging said air-gap to determine the effective dimensions of said air-gap and hence determining the quantity of flux linking said secondary winding and the value of the secondary current.
- 20 4. A transformer capable of delivering desired maximum current to its load, comprising a core including shunt core means, a primary winding and a secondary winding having a plurality of secondary coil sections mounted on the core with said shunt core means extending magnetically around individual secondary coil sections and presenting a corresponding plurality of shunt magnetic paths including fixed air-gaps magnetically between said coil sections and said primary winding, and means for presenting a magnetic path around all of said fixed air-gaps to simultaneously determine the effectiveness of each of the same and hence determining the quantity of flux linking said primary and secondary winding coil sections and the value of the secondary current therein.
